UNITED STATES PATENT OFFICE.

EDWARD C. FLETCHIER, OF INDIANAPOLIS, INDIANA, ASSIGNOR TO THE
INDIANAPOLIS CHAIN AND STAMPING COMPANY, OF SAME PLACE.

DESIGN FOR A BLOCK FOR BICYCLE-CHAINS.

SPECIFICATION forming part of Design No. 27,223, dated June 15, 1897.

Application filed October 13, 1896. Serial No. 608,785. Term of patent 14 years.

To all whom it may concern:

Be it known that I, EDWARD C. FLETCHIER, a citizen of the United States, residing at Indianapolis, in the county of Marion and State 5 of Indiana, have invented and produced a new and original Design for Blocks for Bicycle and other Pitch Chains, of which the following is a specification.

In the accompanying drawings, Figure 1 10 represents a side view; and Fig. 2, a sectional view taken in the plane of the line *a a'*, Fig. 1, and showing a block embodying my new design.

My design consists in a chain-block the 15 inner face of which is sinuous, it being presented by three gradually-merging graceful curves due to a central depression or recess and the rounded faces of end heads. In 20 striking contrast the outer or back face is straight, but so merging with the rounded end heads that the latter are almost circular.

A refers generally to the block, which is, as indicated in Fig. 2, a body in width about 25 equal to the depth of the central part. The end heads B are so regularly rounded that their under faces *b* present graceful curves which merge gradually with the central de-

pression *c*, thus imparting to the inner face of the block an attractive appearance of sinuous character.

In marked contrast to the inner face, which I have above described, the back or outer face *d* is straight, thus imparting a severely plain appearance at this part of the block, which in connection with the highly-ornamental inner 30 face renders the block decidedly characteristic in its appearance.

The heads B B have each a transverse opening *e*, which is approximately the radial center for the major portion of the rounded 40 face of the head.

A bicycle-block embodying my new design is of neat and pleasing appearance.

I claim—

The within-described design for blocks for 45 bicycle and other pitch chains, substantially as set forth.

In testimony that I claim the design above set forth I affix my signature in presence of two witnesses.

EDWARD C. FLETCHIER.
